UNITED STATES PATENT OFFICE.

FREDERICK D. SWEET, OF ELYRIA, OHIO.

EXPLOSIVE-ENGINE.

SPECIFICATION forming part of Letters Patent No. 690,481, dated January 7, 1902.

Application filed April 10, 1900. Serial No. 12,375. (No model.)

To all whom it may concern:

Be it known that I, FREDERICK D. SWEET, a citizen of the United States, residing at Elyria, in the county of Lorain and State of Ohio, have invented a certain new and useful Improvement in Explosive-Engines, of which the following is a full, clear, and exact description, reference being had to the accompanying drawings.

10 The object of the invention is to provide an explosion-engine which will be durable, efficient, easy-running, and self-governing.

The improvements relate to the means for operating the several valves employed in 15 proper sequence, to the means whereby the carbureter is caused to act at the proper time relative to the other parts of the engine to form the explosive mixture and to deliver it into the explosion-chamber, and to the means 20 for automatically governing the operation of the engine, all of which will be hereinafter described, and pointed out definitely in the claims.

In the drawings, Figure 1 is a front elevation of the engine when the exhaust-valve is 25 open. Fig. 2 is a vertical sectional view of the carbureter and of the shaft by which the carbureter-valve, the exhaust-valve, and the igniter are operated. Fig. 3 is a sectional plan view on line 3-3 of Fig. 1. Fig. 4 is a sectional view through the explosion-chamber and exhaust-chamber, designed particularly for showing the igniter; and Fig. 5 is a sectional plan view showing the means for operating 30 the igniter.

35 The engine is constructed to operate according to the Otto cycle, and the following is a description of the engine as shown in which my invention is embodied.

40 Referring to the parts by letters, A represents the cylinder, which has near its closed end a port *a*, through which the explosive mixture enters the cylinder and the exploded gas escapes therefrom. This port is always open

45 and connects the cylinder with the explosion-chamber *F*, which is located at one side of the cylinder. An exhaust-chamber *H*, located below the explosion-chamber, is separated therefrom by a partition *h*, in which is a port *h'*.

50 An exhaust-valve *E* is adapted to close this port and is normally held down upon its seat

by means of a spring *e*, which surrounds the valve-stem and thrusts endwise against a collar *e'* on the valve-stem and against the lower wall of the explosion-chamber, through which 55 the valve-stem passes. The exhaust-pipe *I* is connected with said exhaust-chamber. A carbureter *B* is connected at its upper end through the port *f* with the explosion-chamber *F*. A valve *K*, which when it opens moves 60 inward—that is, toward the explosion-chamber—is held to its seat by a spring *k'*, which thrusts against an adjustable nut *k''* on the valve-stem *k* and against a fixed bar *f'*.

The piston *M* is connected by an ordinary 65 connecting-rod *m* with the crank *n* on the shaft *N*. A shaft *D*, which is mounted at right angles to the shaft *N*, receives its motion therefrom through two beveled gears *d'* and *n'*, which are secured to said two shafts, 70 respectively, and are so proportioned that the shaft *D* revolves half as fast as the shaft *N*.

A sleeve *G* surrounds the shaft *D* and has a tongue-and-groove connection therewith, whereby they must rotate together, but the 75 sleeve may move endwise upon the shaft. The shaft passes through a fixed bracket *P*, in which it has a bearing. A roller *g*, which is mounted on the side of the sleeve *G* near its lower end, is adapted to ride upon the top 80 face of the bracket *P* and upon the cam *p*, which is fixed to the said face as the shaft and sleeve are revolved. It is clear, therefore, that during a part of each revolution of the shaft *D* the sleeve *G* will be raised by the 85 action of the fixed cam *p* upon the roller *g*.

The sleeve *G* passes through a hole in an arm *S*, which is pivoted to a fixed support. A part of the sleeve *G* which is in the embrace of this arm has an annular groove *g'*, which 90 fits the hole in the arm, wherefore the up-and-down movement of the sleeve *G* must necessarily be accompanied by a like movement of the arm *S*. The upper end of the sleeve *G* lies just beneath the lower end of the stem of the exhaust-valve *E*, which stem rests upon said sleeve *G*. It will be understood, therefore, that every time the sleeve *G* is raised the exhaust-valve *E* is lifted from its seat. This sleeve *G* also carries two cams 95 *g' g''*. When the sleeve is in its lowest position, the cam *g'* is adapted to actuate the

igniter, and the cam g^2 is adapted to operate a valve which controls the admission of gasoline to the carburetor.

The igniter consists of the following mechanism: A rock-shaft T is mounted in and passes through an insulated plug f^3 , which closes a hole in the top wall of the explosion-chamber. On the lower end of this rock-shaft, and consequently within the explosion-chamber, is a laterally-extended contact-arm t , which normally is held against a stop-pin f^4 on the under side of the said plug by means of a rat-trap spring t' , which embraces the shaft T and is secured at its ends to the shaft and to the plug. This shaft, it will be understood, is insulated from the other parts of the mechanism, and one wire x of a sparking-circuit is connected with this shaft. Another rock-shaft V passes through the partition h and through the lower wall of the exhaust-chamber and has its bearing for most part in a sleeve h^5 , secured to said lower wall. On the inner end of this rock-shaft within the explosion-chamber is a laterally-extended contact-arm v , which normally lies in contact with a fixed pin h^6 and is held in such contact by means of a rat-trap spring v' , which surrounds the shaft and is secured at one end to it and at the other end to the said bearing-sleeve h^5 . To the lower end of this rock-shaft a laterally-projecting arm v^2 is secured, and this arm is in a position to be engaged by the cam g' when the sleeve G is in its lower position. When during the revolution of the sleeve G this cam does strike this arm v^2 , it turns the shaft against its spring, thereby moving the contact-arm v against the contact-arm t . This results in the rubbing together of these contact-arms and in the rocking of the rock-shaft T. When the cam g' leaves its engagement with the arm v^2 , the two rat-trap springs $v' t'$ move the two rock-shafts rapidly in the contrary direction until the contact-arms again come in contact with the said pins. Just before this happens, however, the contact-arms separate, wherefore, because one wire x' of the sparking-current is electrically connected with said shaft V, because it is connected with the metallic frame of the machine, an electric spark passes between these two contact-arms, wherefore the explosive mixture is ignited. The primary advantages of the particular construction described of the contact-arms are that they automatically clean themselves by their rubbing contact and the contacting surfaces are always bright. Moreover, they are self-adjusting to compensate for wear, for the rat-trap springs will act to return the contact-arms to the relative position shown and into contact with the stop-pins however much these surfaces may be worn. Expensive platinum points are therefore not needed, and these arms may be made of any comparatively inexpensive material. I prefer to use nickel-steel.

The carburetor includes a vertical tube B,

connected at its upper end, as before stated, with the explosion-chamber. The lower end of this tube is closed by a check-valve b , which is held to its seat by a spring b' , whose tension may be adjusted. The carburetor-tube B is connected near its lower end with a valve-casing b^2 , having a recess b^3 , which is connected by means of a pipe U with a gasoline supply-tank. The opening or port b^4 in this casing contains a valve b^5 , which is seated by a spring b^6 , and it has a stem b^7 , which extends laterally into a position to be engaged by the cam g^2 . On the side of the valve toward which it opens the recess in the valve-casing passes downward to form a pocket b^8 , into which the gasoline may flow, and a small tube b^9 communicates with this pocket and enters the carburetor-tube and is turned upward. This same pocket is in open communication with the outer air through the small port b^{10} . In the carburetor-tube are a plurality of screens b^{11} , which act to cause the admixture of the gasoline-vapor and the air.

The construction of the parts having been described, a brief description of their operation is in order.

In Fig. 1 the position of the parts is shown when the piston is moving upward, expelling the exploded gases. It will be noticed that the sleeve G is raised at this time by reason of the contact of the roller g with the fixed cam p, and therefore said exploded gas passes freely from the explosion-chamber into the exhaust-chamber and out through the exhaust-pipe I. When the sleeve G is thus raised, the cams $g' g^2$ thereon are raised above the arms with which they are intended to engage, and they therefore cannot perform their functions. When, however, the sleeve falls, as it ordinarily does when it has been revolved past the fixed cam p, at which time the piston will have reached the upper end of its stroke, the exhaust-valve will close. Then as the piston goes down it sucks into the explosion-chamber out of the carburetor its charge of the explosive mixture. Just before the piston begins to move down the cam g^2 strikes the valve-stem b^7 , and opens the valve b^5 , and permits a small quantity of gasoline to flow into the pocket b^8 . This valve is only kept open a very short space of time. Then the suction of the piston sucks air through the port b^{10} into the carburetor and also causes the vaporization of the gasoline as the air passes through, which gasoline-vapor passes up through the tube b^9 into the carburetor-tube B, mingling with the air and with other air which enters the bottom of the carburetor-tube past the valve b . This mixture constitutes the explosive mixture, which, as before stated, is drawn into the explosion-chamber and into the cylinder while the piston is moving downward. The piston then moves upward and compresses its charge of the explosive mixture, and just as it reaches the top of its stroke the cam g' , which has previously en-

gaged with arm v' and rocked the rock-shaft V to cause the contact of the two contact-arms v and t in the explosion-chamber and the completion of the electric circuit, leaves 5 its engagement with said arm v' , whereupon the rat-trap spring moves the two shafts in the reverse direction and causes the sudden separation of the contact-points, whereby a spark is made, the mixture ignited, and the 10 explosion takes place. These operations are repeated indefinitely. Means are provided, however, whereby the engine is governed so that it cannot run away. On the shaft D are secured two laterally-projecting arms $u\bar{u}$, to 15 which are pivoted two bell-crank levers $u'\bar{u}'$, which have weights $w^3\bar{w}^3$ on the lower ends of their vertical arms. The horizontal arms are connected by links $u^4\bar{u}^4$ with a vertically-movable sleeve u^5 , which embraces the shaft. 20 This sleeve is operatively connected with the lower end of a bent lever W , which is pivoted to the bracket P . When the shaft rotates with sufficient rapidity, the balls are thrown outward, the collar is drawn downward, and consequently this lever, or rather its upper end, is thrown inward, so that an adjustable arm w' , carried by said lever, engages beneath the outer end of the arm S , and thus holds it up, and it in turn holds up the sleeve G . When 25 the sleeve is up, the exhaust-valve is open, and therefore the piston may move up and down freely, because the air can pass freely into the upper end of the cylinder past said valve. When the engine slows down, the governor-balls will drop and the described parts move in the reverse direction, whereby this arm S will be released, wherefore the sleeve G will drop to its normal position, where it can operate the igniter and the carbureter- 30 valve.

Having described my invention, I claim—

1. In an explosive-engine, in combination, a rotatable shaft, a sleeve thereon adapted to rotate with the shaft and slide longitudinally 45 upon it, a cam connection between said sleeve and a relatively stationary part for causing said sleeve to shift longitudinally on the shaft, an exhaust-valve, means for operating it extending into the path of said sleeve whereby 50 the shifting of the sleeve opens the exhaust-valve, a carbureter-valve, a cam on said sleeve for opening the same said cam operating at a different point in the rotation of the same from the cam connection which causes the shifting 55 of the sleeve, substantially as described.

2. In an explosive-engine, in combination, a shaft, a sleeve thereon revoluble therewith and also shiftable longitudinally thereon, an exhaust-valve having its stem alined with said 60 shaft and carrying a shoulder adapted to be engaged by said sleeve when shifted, an igniter-shaft, a cam on the sleeve for operating such shaft, a cam connection between said sleeve and a stationary part for shifting the 65 sleeve to open the exhaust-valve, said two cams operating at different parts of the rotation of the sleeve, substantially as described.

3. In an explosive-engine, in combination, a shaft, a sleeve thereon rotating with the shaft, and shiftable longitudinally, a cam connection with a stationary part for causing such longitudinal shifting, an exhaust-valve having its stem parallel with said shaft and carrying a shoulder adapted to be engaged by the sleeve to open the valve, an igniter-shaft 70 parallel with the exhaust-valve, a carbureter-valve controlling the hydrocarbon admission, a pair of cams on said sleeve adapted in their rotation to operate the igniter, and open the hydrocarbon-valve, substantially as 75 described.

4. In a hydrocarbon-engine, in combination, a rotatable shaft, a sleeve thereon rotating with the shaft and shiftable on it, a cam connection causing such shifting of the sleeve, 85 an arm or collar movable longitudinally with the sleeve, a centrifugal governor on said shaft, an arm movable thereby into the path of said collar, an exhaust-valve operated by the longitudinal shift of said sleeve whereby 90 when the speed becomes too great the governor may lock the shifting of the sleeve and thus hold the exhaust-valve open, substantially as described.

5. In an explosive-engine, in combination, 95 a shaft, a sleeve therein rotatable therewith and also longitudinally shiftable thereon, a cam connection for causing such longitudinal shift, an arm or collar movable longitudinally with the sleeve, an arm controlled by a centrifugal governor adapted when the speed is too great to engage said arm or collar on the sleeve, an igniter, a hydrocarbon-valve, cams on said sleeve adapted to normally operate said igniter and hydrocarbon-valve but rendered inoperative when the governor operates as described, and an exhaust-valve operated by the longitudinal shifting of the sleeve and adapted to be held open thereby when the governor so operates, substantially as de- 100 105 scribed.

6. In an explosive-engine, in combination, a rotatable sleeve, a cam connection for giving it a longitudinal shift as it rotates, a collar or arm movable longitudinally with said 115 sleeve, a centrifugal governor, a pivoted arm operated thereby, an adjustable arm moved by the governor-arm and adapted to lie in the path of the collar or arm which is shiftable with the sleeve thereby rendering inoperative 120 the longitudinal shifting mechanism, and governing-valves normally controlled by said sleeve but rendered inoperative when the described engagement of the governor-arm takes place, substantially as described. 125

7. In an explosive-engine, in combination, a rotatable shaft, a bracket concentric therewith, two bell-cranks pivoted to said bracket, weights on one of the ends of said bell-cranks, a shiftable collar on said shaft, links connecting the other ends of the bell-cranks with the collar, a sleeve on said shaft, a cam carried thereby, a valve or igniter operated by said cam, a cam connection adapted to cause a 130

longitudinal shifting of said sleeve as it rotates, an exhaust-valve operated by said shifting, and an arm moved by the governor to engage a projection movable with said sleeve
5 and hold such shifting cam connection out of operation and thus retain the exhaust-valve open, substantially as described.

In testimony whereof I hereunto affix my signature in the presence of two witnesses.

FREDERICK D. SWEET.
